UNITED STATES PATENT OFFICE

100,485

DESIGN FOR A TRAILER OR SIMILAR ARTICLE

Vernon Harlan Broomall, Salem, Ohio, assignor to Mullins Manufacturing Corporation, Salem,
Ohio, a corporation of New York

Application April 29, 1936, Serial No. 62,363

Term of patent 14 years

To all whom it may concern:

Be it known that I, Vernon Harlan Broomall, a citizen of the United States of America and residing at Salem, in the county of Columbiana and State of Ohio, have invented a new, original, and ornamental Design for a Trailer or Similar Article, of which the following is a specification, reference being made to the accompanying drawing, forming part thereof.

Fig. 1 is a side elevational view of a trailer showing the new design.

Fig. 2 is a front elevational view without the running gear looking substantially on line 2—2 of Fig. 1.

Fig. 3 is a rear elevational view without the running gear taken substantially on line 3—3 of Fig. 1.

Fig. 4 is a side elevational view without the running gear showing the trailer body with the top open.

I claim:

The ornamental design for a trailer or similar article substantially as shown.

VERNON HARLAN BROOMALL.
